UNITED STATES PATENT OFFICE.

CHARLES F. REEPS AND FRED G. REEPS, OF OAK PARK, ILLINOIS.

AUTOMATIC MUSIC-TRACKER.

1,194,424.

Specification of Letters Patent. Patented Aug. 15, 1916.

Application filed March 23, 1912. Serial No. 685,829.

To all whom it may concern:

Be it known that we, CHARLES F. REEPS and FRED G. REEPS, citizens of the United States of America, and residents of Oak Park, Cook county, Illinois, have invented a certain new and useful Improvement in Automatic Music-Trackers, of which the following is a specification.

Our invention relates to the perforated music sheet and tracker bar employed in playing musical instruments, such, for example, as the piano player or player piano of well known form and character.

The object of our invention is to provide novel and improved means controlled by an admission of air through the music note or other perforations of the sheet for automatically preserving the necessary relation or alinement between the said perforations and the openings in the face of the tracker bar.

To this and other useful ends our invention consists in matters hereinafter set forth and claimed.

In the accompanying drawings,—Figure 1 is a front elevation of a music sheet and tracker bar mechanism involving the principles of our invention. Fig. 2 is an enlarged view of a portion of said mechanism. Fig. 3 is a perspective of one end portion of the said tracker bar.

As thus illustrated, our invention comprises the usual upper and lower rolls or spools A and B, and the sheet of perforated paper C called the music sheet is unwound from the roll A to the roll B to play the music, and is then rewound upon the roll A, in the usual or any suitable manner. The music sheet travels across the face or outer edge of the tracker bar D, which latter is mounted for endwise shift and provided with the usual openings d for the air. These openings d coöperate with the note perforations c in the music sheet to control the playing mechanism (not shown) in the usual or any suitable manner.

At one end the tracker bar is connected by an adjustable screw coupling E with the metal strap e secured to the movable walls of the two bellows e¹ and e², whereby when either bellows expands the other contracts, and whereby the tracker bar is shifted endwise. These bellows or pneumatics are connected by pipes e³ and e⁴ with the usual exhaust or pumping apparatus (not shown) of a playing apparatus of this kind. In addition to the usual openings d, the tracker bar

has two parallel rows of much smaller holes d¹ and d², the holes d¹ being connected with the pipe d³, leading to the pneumatic e¹, and the holes d² being connected by a pipe d⁴ with pneumatic e². It will be seen that the holes d¹ are staggered relatively to the holes d², whereby the note perforations c are each able to pass between a hole d¹ and a hole d² when these perforations are traveling in exact alinement with the openings d, as shown more clearly in Fig. 2.

The operation is as follows: While the music sheet is traveling in alinement with the tracker bar openings, the mechanism remains in normal condition. Suppose, however, that the sheet shifts slightly to the left. In such case the note perforations c pass over holes d¹, thereby allowing air to pass into the pipe d³, and into the pneumatic e¹. This causes the latter to expand and the pneumatic e² to contract, thus causing the coupling E to pull the tracker bar to the left until the alinement is restored. If the sheet shifts to the right, then the air passes through the perforations c and into the holes d², thereby permitting air to enter the pneumatic e² by way of the pipe d⁴. This causes the pneumatic e² to expand and the pneumatic e¹ to contract, and as a result the tracker bar is pushed to the right until the alinement is restored. Thus the note perforations in the music sheet constitute a part of the means for automatically preserving the alinement between the music sheet and the tracker bar.

With this method the means for preserving alinement does not become impaired by tearing of the edge of the music sheet. Where the edges of the sheet are depended upon to control the automatic alinement, the arrangement soon becomes useless, and even detrimental, owing to the fact that the edges of these sheets almost invariably become torn and ragged. But with our invention this can do no harm, and the automatic alinement is always operative.

By means of the screw coupling E the tracker bar D can be manually adjusted endwise until the openings f are in line with the note perforations c in the sheet. This alinement for any certain sheet is then automatically preserved in the manner described.

An important feature of our invention is the K-bellows formed by the two pneumatics l¹ and l² having their movable walls hinged at a common point and connected by the

strap or bracket *e* to make them work alternately. It is also an important consideration that the tracker bar operated by said bellows has the holes d^1 and d^2 located out of line with the openings *d* of said bar, whereby only a slight shift of the sheet in either direction is sufficient to produce the desired result. In addition it will be seen that each and every note perforation is operative to control the automatic tracking mechanism. Those portions of the sheet which are least subject to wear are employed for controlling the said mechanism.

It will be seen that the holes d^1 are all lefts—that is to say, that each one coöperates with the left hand edge of all of the note perforations in a certain row, so that each one of these holes is uncovered by a slight shifting of the music sheet to the left.

Similarly, all of the holes d^2 are rights—that is to say, each hole is controlled by the right hand edge of each note perforation in a certain row, whereby each of these holes is uncovered by a slight displacement of the music sheet to the right. The holes thus termed lefts are all interconnected within the body of the tracker bar, in the manner shown, and the holes termed rights are all interconnected within the body of the tracker bar. Thus there are two holes opposite each space between the openings *d*, one hole being a right, and the other hole being a left. With this arrangement each row of note perforations is forced to travel without room to spare, so to speak, between the two holes, a right and a left, and consequently each note perforation employs both edges thereof,—that is to say, the right and left longitudinal edges, for controlling the means by which the alinement is automatically preserved. By arranging the holes in such manner that the so-called rights are all in the one row, and the so-called lefts all in another row, it is possible to greatly simplify the arrangement and to render the mechanism for preserving the alinement very sensitive and responsive.

What we claim as our invention is:

1. A player mechanism for musical instruments, comprising a music sheet provided with perforations disposed along parallel lines, a tracker bar provided with openings coöperating with the perforations of said sheet, and means controlled by the note perforations of said sheet for automatically preserving alinement thereof with the openings of said tracker bar, having two rows of holes extending along the tracker bar, the holes of each row being connected together, and the holes of one row being staggered relative to those of the other row, each note perforation passing between a hole of one row and a hole of the other row, each pair of holes thus formed being individual to a single line of note perforation, the tracker bar having two separate longitudinal passages, the holes of one row communicating with one passage, and the holes of the other row communicating with the other passage, and said holes being disposed in staggered relation to each other, substantially as and for the purpose set forth.
2. A player mechanism for musical instruments, comprising a traveling music sheet provided with perforations disposed along parallel lines, a tracker bar provided with openings coöperating with the perforations of said sheet, and means controlled by the note perforations of said sheet, for automatically preserving alinement thereof with the openings of said tracker bar, some of which holes are brought within the paths of travel of said note perforations by the lateral shift of the sheet in either direction, there being a right and left hole for each of said perforations, said mechanism being controllable by the opposite edges of each note perforation.
3. A player mechanism for musical instruments, comprising a traveling music sheet provided with perforations disposed along parallel lines, a tracker bar provided with openings coöperating with the perforations of said sheet, and means controlled by the note perforations of said sheet for automatically preserving alinement thereof with the openings of said tracker bar, having holes disposed in the face of the tracker bar and in staggered relation to the said openings, the said holes being divided into two groups, and the members of each group being interconnected within the body of said tracker bar, together with a single connection to said tracker bar for each group.
4. A player mechanism for musical instruments, comprising a traveling music sheet provided with perforations disposed along parallel lines, a tracker bar provided with openings coöperating with the perforations of said sheet, and means controlled by the note perforations of said sheet, for automatically preserving alinement thereof with the openings of said tracker bar, including two rows of holes extending along the tracker bar, the holes of each row being connected together, and the holes of one row being staggered relative to those of the other row, each note perforation passing between a hole of one row and a hole of the other row, each pair of holes thus formed being individual to a single line of note perforation, the tracker bar having two separate longitudinal passages, the holes of one row communicating with one passage, and the holes of the other row communicating with the other passage, and said holes being disposed in staggered relation to each other, substantially as and for the purpose set forth.
5. A player mechanism for musical instruments, comprising a traveling music sheet provided with perforations disposed along parallel lines, a tracker bar provided with openings coöperating with the perforations of said sheet, and means controlled by the note perforations of said sheet, for automatically preserving alinement thereof with the openings of said tracker bar, some of which holes are brought within the paths of travel of said note perforations by the lateral shift of the sheet in either direction, there being a right and left hole for each of said perforations, said mechanism being controllable by the opposite edges of each note perforation.

one row communicating with each other and the holes of the other row communicating with each other, internally of said tracker bar.

2. A player mechanism for musical instruments, comprising a traveling music sheet provided with perforations disposed along parallel lines, a tracker bar provided with openings coöperating with the perforations of said sheet, and means controlled by the note perforations of said sheet, for automatically preserving alinement thereof with the openings of said tracker bar, operated only by air passing through the perforations of the sheet, including holes in said tracker bar, some of which holes are brought within the paths of travel of said note perforations by the lateral shift of the sheet in either direction, there being a right and left hole for each of said perforations, said mechanism being controllable by the opposite edges of each note perforation.

3. A player mechanism for musical instruments, comprising a traveling music sheet provided with perforations disposed along parallel lines, a tracker bar provided with openings coöperating with the perforations of said sheet, and means controlled by the note perforations of said sheet for automatically preserving alinement thereof with the openings of said tracker bar, having holes disposed in the face of the tracker bar and in staggered relation to the said openings, the said holes being divided into two groups, and the members of each group being interconnected within the body of said tracker bar, together with a single connection to said tracker bar for each group.

4. A player mechanism for musical instruments, comprising a traveling music sheet provided with perforations disposed along parallel lines, a tracker bar provided with openings coöperating with the perforations of said sheet, and means controlled by the note perforations of said sheet, for automatically preserving alinement thereof with the openings of said tracker bar, including two rows of holes extending along the tracker bar, the holes of each row being connected together, and the holes of one row being staggered relative to those of the other row, each note perforation passing between a hole of one row and a hole of the other row, each pair of holes thus formed being individual to a single line of note perforation, the tracker bar having two separate longitudinal passages, the holes of one row communicating with one passage, and the holes of the other row communicating with the other passage, and said holes being disposed in staggered relation to each other, substantially as and for the purpose set forth.

5. A player mechanism for musical instruments, comprising a traveling music sheet provided with perforations disposed along parallel lines, a tracker bar provided with openings coöperating with the perforations of said sheet, and means controlled by the note perforations of said sheet, for automatically preserving alinement thereof with the openings of said tracker bar, some of which holes are brought within the paths of travel of said note perforations by the lateral shift of the sheet in either direction, there being a right and left hole for each of said perforations, said mechanism being controllable by the opposite edges of each note perforation.

sheet provided with perforations disposed along parallel lines, a tracker bar provided with openings coöperating with the perforations of said sheet, and means controlled by the note perforations of said sheet, for automatically preserving alinement thereof with the openings of said tracker bar, including holes disposed in the face of the tracker bar and in staggered relation to the 5 said openings, the said holes being divided into two groups, and the members of each group being interconnected within the body of said tracker bar, together with a single connection to said tracker bar for each 10 group, and said holes being disposed in staggered relation to each other, substantially as 15 and for the purpose set forth.

6. A player mechanism for musical instruments, comprising a traveling music sheet provided with perforations disposed along parallel lines, a tracker bar provided with openings coöperating with the perforations of said sheet, and means controlled by both side edges of each and every note perforation of said sheet, by lateral shift of the sheet in opposite directions, for automatically preserving alinement thereof with the openings of said tracker bar, said means having two rows of holes in said tracker bar, 20 the holes of one row being disposed in staggered relation to the holes of the other row, and the holes in the same row being interconnected within the tracker bar.

7. A player mechanism for musical instruments, comprising a traveling music sheet provided with perforations disposed along parallel lines, a tracker bar provided with openings coöperating with the perforations of said sheet, and means controlled by the note perforations of said sheet, for automatically preserving alinement thereof with the openings of said tracker bar, including two rows of holes extending along 25 the tracker bar, the holes of each row being connected together, and the holes of one row being staggered relative to those of the other row, each note perforation passing between a hole of one row and a hole of the other row, each pair of holes thus formed 30 being individual to a single line of note perforations, the tracker bar having two separate longitudinal passages, the holes of one row communicating with one passage, and the holes of the other row communicating 35 with the other passage, said means also comprising a single adjustable connection for causing relative shift of said sheet and tracker bar, and a pair of bellows having movable walls rigidly connected together to 40 operate said connection in opposite directions.

8. A player mechanism for musical instruments, comprising a traveling music sheet provided with perforations disposed 45 along parallel lines, a tracker bar provided

with openings coöperating with the perforations of said sheet, and means controlled by the note perforations of said sheet, for automatically preserving alinement thereof with the openings of said tracker bar, having 50 holes disposed in the face of the tracker bar, in staggered relation to the said openings, the said holes being divided into two groups, and the members of each group being interconnected within the body of said 55 tracker bar, together with a single connection to said tracker bar for each group, said means also comprising a single adjustable element for causing relative shift of said sheet and tracker bar, and a pair of bellows 60 having movable walls rigidly connected together to operate said element in opposite directions.

9. A player mechanism for musical instruments, comprising a traveling music sheet provided with perforations disposed along parallel lines, a tracker bar provided with openings coöperating with the perforations of said sheet, and means controlled by both side edges of a note perforation of said 65 sheet, by lateral shift of the sheet in either direction, for automatically preserving alinement thereof with the openings of said tracker bar, said means having a pair of holes in said tracker bar, one at each side of 70 said perforation, disposed one ahead of the other in the direction of movement of said sheet.

10. The combination of a tracker having the usual row of apertures and also having 75 two supplemental rows of apertures in the rear of the usual row of apertures, said supplemental apertures being located on opposite sides of the bridge spaces of the tracker, and means for shifting the music sheet relatively to the tracker, said means being actuated through the medium of said supplemental apertures.

11. The combination of a tracker having the usual row of apertures and also having 80 two supplemental rows of apertures in the rear of the usual row of apertures, said supplemental apertures being located on opposite sides of the bridge spaces of the tracker, and means for bringing about a relative 85 movement of the music sheet and tracker board in a direction longitudinally of the tracker, said means being operated through the medium of said supplemental apertures.

12. The combination of a tracker having 90 the usual row of apertures and also having two rows of supplemental apertures, and means for producing a relative movement between the tracker and music sheet in a direction lengthwise of the tracker, said means being operable through said supplemental apertures.

13. The combination of a tracker having 95 two rows of apertures, whereof the apertures in the different rows are out of aline- 100

ment crosswise of the tracker, and mechanism for producing a relative shifting movement between the tracker and music sheet, said mechanism being operable to produce 5 a shifting movement in one direction through the medium of the apertures of one row and in the opposite direction through the apertures in the other row.

14. The combination of a tracker having 10 two sets of apertures, whereof the apertures in the two sets are out of alignment crosswise of the tracker, a double bellows, pneumatic connections between said apertures and said bellows, one set of apertures being 15 connected with one part of the bellows and the other set to the other part, and mecha-

nism for producing a relative movement between the tracker and music sheet connected with and operated by said bellows.

15. A tracker having a set of ports for co-operation with the music sheet apertures, and also having two rows of supplemental ports whereof the ports of one row are at one side of the bridge spaces, and the ports of the other row at the other side thereof. 25
